UNITED STATES PATENT OFFICE.

JOHN J. KENNEY, OF PITTSBURGH, PENNSYLVANIA.

THERMOSTATICALLY-ACTUATED VALVE.

Application filed December 29, 1924. Serial No. 758,567.

The present invention relates broadly to valves, and more particularly to snap-action valves of the thermostatic type adapted to control the supply of a fluid, such as fuel gas, although the utility of the invention is not limited in this respect.

Valves of this character are generally complicated and therefore expensive to build and easy to get out of order. By the present invention, I have provided a construction consisting of a relatively small number of parts and in the preferred form of which the action of the thermostat element is transmitted directly to the valve through a single lever. I also provide for sufficient lost motion between the valve-operating lever and the valve to give the thermostat element a suitable working temperature range within which the valve will remain either in its closed or its open position, and at the limits of which the valve will either open or close with a sudden snap-action.

In the accompanying drawings:—

Figure 1 is a longitudinal section through a valve mechanism and its operating thermostat constructed in accordance with a preferred embodiment of my invention;

Figure 2 is a detail sectional view showing the valve in open position;

Figure 3 is a detail sectional view on the line III—III of Figure 1;

Figure 4 is an elevation of the valve-operating lever;

Figures 5 and 6 are detail views of the pin intermediate the non-expansive member of the thermostat and the valve-operating lever, and

Figure 7 is a detail sectional view similar to Figure 2, showing a modified form of the invention.

Referring to the preferred form of the invention illustrated in Figures 1 and 2, the reference numeral 2 designates the valve casing having an inlet connection 3 and an outlet connection 4. Intermediate the ports of these connections the casing is provided with a seat 5 for a valve 6, which may be normally urged towards its seat by a spring 7. Access to the casing is provided by removing the screw closure 8, thereby permitting the parts of the valve mechanism to be removed at will for cleaning or replacing, as may be necessary. The closure has a sleeve 9 and the valve has a cylindrical boss 10 projecting into said sleeve but of slightly smaller external diameter than the internal

diameter of said sleeve. The spring 7 is located in the sleeve 9 and abuts at one end against the bottom thereof and at its other end against the top of the boss 10.

Extending rearwardly from the casing is an externally threaded projection 11, whereby the valve casing can be secured to a suitable support. This projection has a bore extending therethrough and through a thickened portion of the wall of the valve casing, and the outer portion of said bore is screw-threaded for the attachment of the tubular expansible member 12 of the thermostat element. Located within the expansible member is the usual non-expansive member 13, which may be of porcelain, for example. The non-expansive member abuts at its outer end against the cap 14 screwed on the outer end of the expansible member, while at its inner end it abuts against a separate pin 15 sliding in the bore of the projection 11, which may, if desired, form a gas-tight sealed joint between the interior of the valve casing and the interior of the expansible member 12.

A valve-operating lever 16 may be extended vertically in the casing 2 and have a rotatable mounting such as oppositely projecting trunnions 17 adjacent its lower end which bear on an annular ledge 18 of the thickened portion of the wall of the valve casing. The pin 15 has its inner end beveled to a knife edge which engages in a shallow transverse groove 19 in the face of the lever 16, said knife edge lying in a horizontal plane slightly above the axis of the trunnions 17. A screw-threaded fulcrum member 20 is adjustably mounted in a screw-threaded bore in the thickened portion of the wall of the casing 2 diametrically opposite the bore in which the pin 15 is positioned. The fulcrum member has a pin 20^a mounted with a loose fit in a socket in its inner end. The pin 20^a has a cone-shaped inner end which engages in a shallow conical recess in the face of the lever 16 opposite the face having the groove 19, the point of the pin lying in a horizontal plane slightly below the axis of the trunnions 17. This loose-fitting pin permits the valve-operating lever to oscillate without causing undue friction between the trunnions 17 and the seat 18, and also facilitates assembly without the necessity of absolute accuracy in machining.

The lever 16 has its upper end positioned within the hollow boss 10 of the valve,

and has a cam or inclined recess 21 in said upper end into which extends a teat 22 projecting downwardly from the top of the boss 10. A stud 23 projects from one face 5 of the lever 16 and is arranged a slight distance below the valve 6, and a cooperating stud 24 projects into the interior of the valve casing from the wall thereof. A coil spring 25 is mounted on these studs and 10 tends to swing the lever in a counter-clockwise direction about the knife edge of the pin 15 as a fulcrum.

When the valve is closed, the normal position of the parts will be as shown in Figure 15 1. The trunnions 17 resting on the ledge 18 support the weight of the lever 16 and take any downward thrust thereon due to the pressure of the valve on the upper end of the lever. It will thus be seen that the 20 point of the pin 20^a and the knife edge of the sliding pin 15 are not subjected to any downward pressure transmitted through the lever 16. When the expansible member 12 of the thermostat element contracts, the pin 15 25 is forced to the right, thereby causing the valve-operating lever 16 to rock in a clockwise direction about the point of the pin 20^a as a fulcrum, and it will be seen that, due to the relative lengths of the lever arms, a 30 relatively slight movement of the pin 15 will result in a relatively large movement of the upper end of the valve-operating lever. The first portion of this movement causes the valve to be slid bodily to the right on its seat 35 5 by the valve-operating lever until the boss 10 contacts with the side *a* of the sleeve 9, and prevents any further lateral movement of the valve. Further movement of the valve-operating lever builds up a gradually 40 increasing pressure between the teat and the cam or incline 21. This condition continues until the pressure is sufficient to overcome the friction between these parts and the action of the spring 7. At this time the 45 valve snaps vertically from its seat and the teat 22 positions itself on the upper end of the lever 16, as illustrated in Figure 2. The valve will remain in its open position until the desired temperature has been attained 50 in accordance with the setting of the thermostat element. Any further increase in temperature will then cause such expansion of the member 12 of the thermostat element as to permit the spring 25 to rock the lever 55 16 in a counter-clockwise direction about the point of the pin 20 as a fulcrum, said lever forcing the pin 15 into the bore of the projection 11. The first portion of this counter-clockwise movement of the lever 16 will 60 result in the valve being bodily moved to the left due to the friction between the teat 22 and the upper end of the lever until the boss 10 engages the left hand side *b* of the sleeve 9 and prevents further lateral movement. 65 Thereafter, further counter-clockwise move-

ment of the lever 16 will result in the upper end of the lever 16 being moved relatively to the teat 22, thereby establishing a condition in which the action of the spring in combination with the character of the contacting 70 surfaces between the lever and valve, permits the valve to move bodily to the right as viewed in Figure 1, and downwardly onto its seat with a snap action.

It will be appreciated that the valve when 75 in its closed position, can slide back and forth on its seat, due to the difference between the external diameter of the boss 10 and the internal diameter of the sleeve 9, and this is also true when the valve is in open position, as shown in Figure 2. This lost motion is provided in order to allow the valve to remain either in its closed position or in its open position through a suitable working temperature range, say about 10°. When 80 the valve is closed, it will assume some normal intermediate position, such as shown in Figure 1, and will slide back and forth on its seat so long as the temperature remains within the working range. This movement further facilitates the operation of the valve in that it permits the building up 85 of a force capable of overcoming the inertia of the valve and the consequent snap movement thereof to the desired position. 90

The setting of the thermostat can be changed by adjusting the fulcrum pin 20. To that end, I provide the pin at its outer end with a disk-like head 26 having a handle 27, whereby the pin can be turned. On 100 this disk-like head I have placed an arrow 28 for cooperation with graduations 29 on the outer end of the projection 30. This projection has its outer end screw-threaded to receive a cap 31. By removing the cap 105 31 the fulcrum pin 20 can be adjusted to the desired position to set the thermostat.

In the modified construction shown in Figure 7, the valve 6' has a solid boss 10', the external diameter of which is substantially the same as the internal diameter of the sleeve 9' of the closure 8'. Projecting downwardly from the valve is an integral centrally located lug 22', the lower end of 110 which engages the upper surface of a horizontal lever 32 pivoted adjacent the wall of the valve casing on a pin 33. This lever has an elongated slot 34 through which the pin 33 projects. At its inner end the lever 32 has a downwardly projecting lug 35 providing a cam shoulder 36 between said lug and the lower surface 37 of the main portion of the lever. The upper end of the valve-operating lever 16' is rounded at 38 for cooperation with said cam shoulder 36. 115 120

In this modified construction, when the expansible member of the thermostat element contracts and causes the valve-operating lever 16' to swing in a clockwise direction, the horizontal lever 32 is slid to 125 130

the right by reason of the engagement of the upper end of the lever 16' with the lug 35 until the pin 33 engages the left hand end of the slot 34 and prevents further lateral movement. Thereafter, any further clockwise movement of the lever 16' builds up an effective pressure between the upper end of said lever and the lug 35, which ultimately causes snap action of the valve and movement of the upper end of the lever 16' under the lower surface of said lug. When the lever 16' moves in a counter-clockwise direction, the horizontal lever 32 is moved to the left until the pin 33 reaches the right hand end of the slot 34, the valve 6' remaining in open position during such movement of the lever 32. Thereafter, any further counter-clockwise movement of the lever 16' establishes a condition in which the action 20 of the spring 7' in combination with the character of the cam surfaces of the lever 16' and lug 35 permits the lever 32 to move bodily to the right as viewed in Figure 7, thereby permitting the valve to snap to 25 closed position.

Certain advantages of the present invention arise from the provision of a valve of such construction that initially a relatively lost motion is obtained which becomes effective for producing a snap action of the valve in either direction.

Further advantages arise from the simplicity of the construction, the ease of adjustment of the valve, and the positive character of the valve movement.

While I have shown and described certain preferred embodiments of my invention, it will be understood that the invention is not limited to the details of construction shown, 40 but that it may be otherwise embodied within the scope of the appended claims without departing from the spirit of the invention.

I claim:

1. In a valve mechanism, a valve casing having a valve seat, a valve cooperating with said seat, a valve-operating lever, a fulcrum member operatively connected with said lever adjacent one end thereof, a thermostat element effective on said lever adjacent said end thereof, a spring for moving said lever in opposition to said thermostat element, said valve having a hollow boss into which the other end of said lever projects, said boss having a teat projecting therefrom and said end of said lever having a cam surface cooperating with said teat, a sleeve within which said boss projects and having a greater internal diameter than the 55 external diameter of said boss, and a spring in said sleeve engaging said boss and urging said valve towards its seat, substantially as described.

2. In a valve mechanism, a casing, a valve 65 having an operating cam movable in either

of two directions, an operating member for said valve having a cam cooperating with said operating cam, and means for moving said operating member to effect bodily movement of the operating cam first in one direction and then in another direction, substantially as described. 70

3. In a valve mechanism, a casing, a valve having an operating cam movable in either of two directions, an operating member for 75 said valve having a cam cooperating with said operating cam, and temperature responsive means for moving said operating member to effect bodily movement of the operating cam first in one direction and 80 then in another direction, substantially as described.

4. In a valve mechanism, a casing, a valve having an operating cam movable in either of two directions, an operating lever for said 85 valve having a cam cooperating with said operating cam, and means for moving said lever to effect bodily movement of the operating cam first in one direction and then in another direction, substantially as described. 90

5. In a valve mechanism, a casing, a valve having an operating cam movable in either of two directions, an operating lever for said valve having a cam cooperating with said 95 operating cam, and temperature responsive means for moving said lever to effect bodily movement of the operating cam first in one direction and then in another direction, substantially as described. 100

6. In a valve mechanism, a casing, a valve normally tending to move in one direction and having an operating cam movable in either of two directions, an operating member for said valve having a cam cooperating 105 with said operating cam, and means for moving said operating member to effect bodily movement of the operating cam first in one direction and then in another direction, substantially as described. 110

7. In a valve mechanism, a valve casing having a valve seat, a valve cooperating with said seat, a valve operating member, cam surfaces between said member and said valve, and means for moving said member to initially produce simultaneous movement of said cam surfaces and then the relative movement thereof, substantially as described. 115

8. In a valve mechanism, a valve casing having a valve seat, a valve cooperating 120 with said seat, a valve operating lever, cam surfaces between said lever and said valve, and means for moving said lever to initially produce simultaneous movement of said cam surfaces and then relative movement thereof, 125 substantially as described.

9. In a valve mechanism, a casing, a valve normally tending to move in one direction and having an operating cam movable in either of two directions, an operating mem- 130

ber for said valve having a cam cooperating with said operating cam, and temperature responsive means for moving said operating member to effect bodily movement of the operating cam first in one direction and then in another direction, substantially as described.

10. In a valve mechanism, a valve casing having a valve seat, a valve cooperating with said seat, a valve operating member, cam surfaces between said member and said valve, and temperature responsive means for moving said member to initially produce simultaneous movement of said cam surfaces and then the relative movement thereof, substantially as described.

11. In a valve mechanism, a casing, a valve having an operating cam movable in either of two directions, an operating member for said valve having a cam cooperating with said operating cam, temperature responsive means for moving said operating member to effect bodily movement of the operating cam first in one direction and then in another direction, and means for varying the temperature at which said temperature responsive means becomes effective, substantially as described.

12. In a valve mechanism, a casing, a valve having an operating cam movable in either of two directions, an operating lever for said valve having a cam cooperating with said operating cam, temperature responsive means for moving said lever to effect bodily movement of the operating cam first in one direction and then in another direction, and means for varying the temperature at which said temperature responsive means becomes effective, substantially as described.

13. In a valve mechanism, a casing, a valve normally tending to move in one direction and having an operating cam movable in either of two directions, an operating member for said valve having a cam cooperating with said operating cam, temperature responsive means for moving said operating member to effect bodily movement of the operating cam first in one direction and then in another direction, and means for varying the temperature at which said temperature responsive means becomes effective, substantially as described.

14. In a valve mechanism, a valve casing having a valve seat, a valve cooperating with said seat, a valve operating member, cam sur-

faces between said member and said valve, temperature responsive means for moving said member to initially produce simultaneous movement of said cam surfaces and then the relative movement thereof, and means for varying the temperature at which said temperature responsive means becomes effective, substantially as described.

15. In a valve mechanism, a valve casing having a valve seat, a valve cooperating with said seat, a valve operating member, means for moving said member, and cams between said member and said valve whereby movements of said member are effective to operate said valve, one of said cams having an initial limited movement in one direction with the other, and a limited movement in another direction relative to the other, whereby there is an initial lost motion between the cams in effecting the operation of the valve to one position.

16. In a valve mechanism, a valve casing having a valve seat, a valve cooperating with said seat, a valve operating member, temperature responsive means for moving said member, and cams between said member and said valve whereby movements of said member are effective to operate said valve, one of said cams having a limited movement with the other in one direction which is ineffectual for operating the valve, and being thereafter movable relatively to the other in another direction for effecting the operation of the valve.

17. In a valve mechanism, a valve casing having a valve seat, a valve cooperating with said seat, a valve operating member, temperature responsive means for moving said member, cams between said member and said valve whereby movements of said member are effective to operate said valve, one of said cams having a limited movement in the casing with respect to the other cam in one direction, which movement is ineffectual for operating the valve, and being thereafter movable relatively to the other in another direction for effecting the operation of the valve, and means for varying the temperature at which said temperature responsive means becomes effective, substantially as described.

In testimony whereof I have hereunto set my hand.

JOHN J. KENNEY.
